FIGURE 1 is a top plan view of a compartmented candy tray, showing my new design;

FIGURE 2 is a side elevational view thereof;

FIGURE 3 is an end elevational view thereof, taken from the left of FIGURE 1;

FIGURE 4 is a fragmentary transverse vertical sectional view taken on the line 4—4 of FIGURE 2 and on a larger scale; and

FIGURE 5 is a fragmentary perspective view of the candy tray.

The design is characterized by a one-piece tray molded with parallel rows of longitudinally elongated diamond-shaped pockets having generally spheroidal bottom walls and with embossed triangular ledges at the ends of said rows, all as shown.

I claim:

The ornamental design for a compartmented candy tray, as shown and described.
